UNITED STATES PATENT OFFICE.

ALMER McDUFFIE McAFFEE, OF PORT ARTHUR, TEXAS, ASSIGNOR TO GULF REFINING COMPANY, OF PITTSBURGH, PENNSYLVANIA, A CORPORATION OF TEXAS.

PRODUCTION OF LOWER-BOILING DISTILLATES FROM HIGHER-BOILING PETROLEUM HYDROCARBONS.

No Drawing.

Application filed April 25, 1925. Serial No. 25,926.

- This invention relates to the production of lower boiling distillates from higher boiling petroleum hydrocarbons, and it comprises the process of distilling higher boiling petroleum hydrocarbons with the aid of anhydrous aluminum chlorid by charging a still with the higher boiling petroleum hydrocarbons and a relatively small amount of anhydrous aluminum chlorid, and distilling, 10 advantageously under agitation of the oil, with immediate removal of vapors from the still until at least 75 per cent of the charge is collected as a distillate which upon assay distillation, shows an amount distilling between 392° F. and 518° F. at least equal to the amount distilling below 392° F.
- I have discovered a way of producing a valuable distillate in large quantities with the use of a relatively small proportion of 20 aluminum chlorid without having to resort to refluxing means during the distillation. In accordance with my invention I distil in such a way as to produce a distillate of a special character. By using not substantially over 3 per cent of aluminum chlorid and advantageously less—as low as 1 per cent—by weight on the higher boiling oil charged to the still and conducting a steady distillation without special means for refluxing, I produce from a given charge a large quantity of lower boiling hydrocarbons. Under the conditions mentioned, there is substantially no loss of aluminum chlorid and any traces of hydrochloric acid 25 formed, in event moist oils are used, may be removed by scrubbing the vapors of the distillate as they leave the still. Of the distillate produced, between 50 and 75 per cent is of the nature of gasoline and kerosene, 30 and from 25 to 50 per cent is of the nature of the original oil charged to the still, differing somewhat in being more refined. Upon redistillation of the distillate in the usual manner the residual higher boiling oil is used 35 as part of the charge for a succeeding aluminum chlorid distillation. It is particularly useful here due to the fact that it contains less sulphur and more saturated hydrocarbons than normal gas oil.
- 40 In one distillation operation which may be considered an embodiment of the present invention, using a 1,000 barrel still, there was charged about 950 barrels of high boiling oil (in this instance, gas oil) which upon test distilled over a range between 406° F. and 708° F. A 1,000 barrel still is one which will hold 1,000 barrels of oil with sufficient vapor space for distillation. This oil was heated to about 300° F. There was then added 1.80 per cent by weight of anhydrous aluminum chlorid in admixture with sufficient warm oil to bring the total charge up to 1,000 barrels. The contents of the still were then further heated. No special precautions for refluxing were resorted to and the vapors were removed as fast as produced. In approximately ten hours distillate appeared in the condenser. The firing of the still was continued and in the next five hours the temperature of the oil in the still was 460° F., the temperature of the vapor in the still at about one or two feet from the top was 445° F., and the temperature at the highest point in the vapor line was 391° F. From this time on the temperature at the highest point in the vapor line exceeded 391° F.
- The distillation was stopped thirty hours after the distillate first appeared in the condenser, or forty hours after the still was fired. The total distillate was collected in one receiver and it comprised 89 per cent of the original charge, the remainder of the charge being accounted for by residual oil in the still and by gas and coke. Ordinarily 50 I carry out the distillation to a point where at least 75 per cent of the charge is collected as distillate.
- An assay distillation of the distillate collected, as a result of the above process using 1.80 per cent by weight of aluminum chlorid, showed 22 per cent distilling up to 392° F., 35 per cent distilling between 392° F. and 518° F., and about 43 per cent distilling above 518° F.
- According to another embodiment of my invention, and by way of illustration, using the same amount of gas oil of the same character as above described, and carrying out the distillation in the same manner, but using 3 per cent of aluminum chlorid by weight on the gas oil charged, there was obtained 83 per cent of total distillate. This distillate, upon assay distillation, showed 35.5 per cent distilling up to 392° F., 36.5 per cent distilling between 392° F. and 518° F., and about 28 per cent distilling above 518° F.

- The processes performed in the way described resulted in the production of a distillate which, upon assay distillation, showed an amount distilling between 392° F. and 518° F. at least equal to the amount distilling below 392° F., but in no instance was there any substantial loss of aluminum chlorid although, it is to be observed that throughout the major portion of the distillation the temperature at the highest point in the vapor line exceeded 391° F. If there is any moisture in the oil as charged there will be a slight formation of hydrochloric acid but the vapors of the hydrochloric acid formed, as well as any traces of aluminum chlorid going over with the vapors can be eliminated by suitable scrubbing apparatus. The distillate is removed from the still as fast as formed. With the amounts of aluminum chlorid stated, the distillate formed during the first few hours of the run showed a preponderance of lower boiling oil in the distillate and as the run progressed and the temperature gradually rose there was a preponderance of higher boiling oil in the distillate, but the amount of aluminum chlorid in the still at any given time was such that it was active in conversion and did not tend to accompany the vapors forward.
- I ordinarily carry out the distillation until there is about 5 to 10 per cent of residual oil left in the still. The distillate produced under these conditions represents 85 per cent of the original charge, the remainder being accounted for as gas and coke. But while these are so far as at present advised, the best working conditions, I may stop the process at a point where 75 per cent of total distillate is collected. In any event the distillate should be of such a character that, upon assay distillation, the amount distilling up to 392° F. will not exceed that amount distilling between 392° F. and 518° F.
- When the distillation is completed to the desired point, the residue in the still may be removed in the usual manner, the aluminum chlorid recovered in accordance with well-known methods, or the aluminum chlorid residue may be removed and the still prepared for a new run in accordance with the process described and claimed in my copending application, Serial Number 680,512, filed December 13, 1923.
- I claim:
1. In the production of lower boiling oils from higher boiling oils with the aid of aluminum chlorid by distillation of oil in the presence of the chlorid, the process which comprises limiting the amount of aluminum chlorid used and heating in such a manner and at such a rate as to produce a distillate, which upon assay distillation will show at least as much distilling below 392° F. and 518° F. as will distill below 392° F.
  2. In the distillation of higher boiling petroleum hydrocarbons with the aid of anhydrous aluminum chlorid, the process which comprises heating in such a manner and at such a rate as to produce a distillate having a greater amount distilling between 392° F. and 518° F. than below 392° F.
  3. In the distillation of higher boiling petroleum hydrocarbons with the aid of anhydrous aluminum chlorid, the process which comprises distilling the higher boiling hydrocarbons in the presence of aluminum chlorid with removal of vapors of distillate as produced and conducting the distillation until the distillate produced will show, upon assay distillation, at least as much distilling between 392° F. and 518° F. as will distill below 392° F.
  4. In the distillation of higher boiling petroleum hydrocarbons with the aid of anhydrous aluminum chlorid, the process which comprises adding not substantially over 3 per cent of aluminum chlorid, conducting the distillation with removal of vapors of distillate as produced until at least 75 per cent of the original charge is collected as distillate which upon assay distillation will show at least as much distilling between 392° F. and 518° F. as will distill below 392° F.
  5. In the production of lower boiling oils from higher boiling oils with the aid of aluminum chlorid by distillation of oil in the presence of the chlorid, the process which comprises limiting the amount of aluminum chlorid used to produce a distillate equal to at least 75 per cent of the original charge, such distillate, upon assay distillation, showing at least as much distilling between 392° F. and 518° F. as distills below 392° F.
  6. In the production of lower boiling oils from higher boiling oils with the aid of aluminum chlorid by distillation of oil in the presence of the chlorid, the process which comprises limiting the amount of aluminum chlorid used to produce a distillate equal to at least 75 per cent of the original charge, such distillate showing, upon assay distillation, not more than 35½ per cent distilling under 392° F.

In testimony whereof, I have hereunto affixed my signature.

ALMER McDUFFIE McAFFEE.

The processes performed in the way described resulted in the production of a distillate which, upon assay distillation, showed an amount distilling between 392° F. and 518° F. at least equal to the amount distilling below 392° F., but in no instance was there any substantial loss of aluminum chlorid although, it is to be observed that throughout the major portion of the distillation the temperature at the highest point in the vapor line exceeded 391° F. If there is any moisture in the oil as charged there will be a slight formation of hydrochloric acid but the vapors of the hydrochloric acid formed, as well as any traces of aluminum chlorid going over with the vapors can be eliminated by suitable scrubbing apparatus. The distillate is removed from the still as fast as formed. With the amounts of aluminum chlorid stated, the distillate formed during the first few hours of the run showed a preponderance of lower boiling oil in the distillate and as the run progressed and the temperature gradually rose there was a preponderance of higher boiling oil in the distillate, but the amount of aluminum chlorid in the still at any given time was such that it was active in conversion and did not tend to accompany the vapors forward.

I ordinarily carry out the distillation until there is about 5 to 10 per cent of residual oil left in the still. The distillate produced under these conditions represents 85 per cent of the original charge, the remainder being accounted for as gas and coke. But while these are so far as at present advised, the best working conditions, I may stop the process at a point where 75 per cent of total distillate is collected. In any event the distillate should be of such a character that, upon assay distillation, the amount distilling up to 392° F. will not exceed that amount distilling between 392° F. and 518° F.

When the distillation is completed to the desired point, the residue in the still may be removed in the usual manner, the aluminum chlorid recovered in accordance with well-known methods, or the aluminum chlorid residue may be removed and the still prepared for a new run in accordance with the process described and claimed in my copending application, Serial Number 680,512, filed December 13, 1923.

I claim:

1. In the production of lower boiling oils from higher boiling oils with the aid of aluminum chlorid by distillation of oil in the presence of the chlorid, the process which comprises limiting the amount of aluminum

chlorid used and heating in such a manner and at such a rate as to produce a distillate, which upon assay distillation will show at least as much distilling below 392° F. and 518° F. as will distill below 392° F.

2. In the distillation of higher boiling petroleum hydrocarbons with the aid of anhydrous aluminum chlorid, the process which comprises heating in such a manner and at such a rate as to produce a distillate having a greater amount distilling between 392° F. and 518° F. than below 392° F.

3. In the distillation of higher boiling petroleum hydrocarbons with the aid of anhydrous aluminum chlorid, the process which comprises distilling the higher boiling hydrocarbons in the presence of aluminum chlorid with removal of vapors of distillate as produced and conducting the distillation until the distillate produced will show, upon assay distillation, at least as much distilling between 392° F. and 518° F. as will distill below 392° F.

4. In the distillation of higher boiling petroleum hydrocarbons with the aid of anhydrous aluminum chlorid, the process which comprises adding not substantially over 3 per cent of aluminum chlorid, conducting the distillation with removal of vapors of distillate as produced until at least 75 per cent of the original charge is collected as distillate which upon assay distillation will show at least as much distilling between 392° F. and 518° F. as will distill below 392° F.

5. In the production of lower boiling oils from higher boiling oils with the aid of aluminum chlorid by distillation of oil in the presence of the chlorid, the process which comprises limiting the amount of aluminum chlorid used to produce a distillate equal to at least 75 per cent of the original charge, such distillate, upon assay distillation, showing at least as much distilling between 392° F. and 518° F. as distills below 392° F.

6. In the production of lower boiling oils from higher boiling oils with the aid of aluminum chlorid by distillation of oil in the presence of the chlorid, the process which comprises limiting the amount of aluminum chlorid used to produce a distillate equal to at least 75 per cent of the original charge, such distillate showing, upon assay distillation, not more than 35½ per cent distilling under 392° F.

In testimony whereof, I have hereunto affixed my signature.

ALMER McDUFFIE McAFFEE.

Certificate of Correction.

It is hereby certified that in Letters Patent No. 1,601,636, granted September 28, 1926, upon the application of Almer McDuffie McAfee, of Port Arthur, Texas, for an improvement in "The Production of Lower-Boiling Distillates from Higher-Boiling Petroleum Hydrocarbons," an error appears in the printed specification requiring correction as follows: Page 2, line 63, claim 1, for the word "below" read *between*; and that the said Letters Patent should be read with this correction therein that the same may conform to the record of the case in the Patent Office.

Signed and sealed this 26th day of October, A. D. 1926.
